UNITED STATES PATENT OFFICE.

DORA LUCKA, OF VIENNA, AUSTRIA-HUNGARY.

ARRANGEMENT FOR CLOSING LEAKS IN SHIPS.

1,107,680.

Specification of Letters Patent. Patented Aug. 18, 1914.

Application filed October 23, 1913. Serial No. 796,865.

To all whom it may concern:

Be it known that I, DORA LUCKA, citizeness of Austria, residing at IX Rossauergasse 4, Vienna, Austria-Hungary, have invented 5 new and useful Arrangements for Closing Leaks in Ships; and I do hereby declare the following to be a full, clear, and exact description of the same.

Hitherto leaks in ships were simply closed 10 with oakum, sailcloth soaked in tar and the like, but this only rarely met the purpose, or in an imperfect manner only.

The present invention relates to an arrangement for closing such leaks in ships, 15 which consists essentially of a bandage which is applied in one or several places on the outside of the vessel and covers the leak, and which is sufficiently strong, and yet of a small weight and elastic, so that it can 20 adapt itself in a close and as watertight a manner as possible to the shape of the vessel and in particular the edges of the break or leak in the skin of the vessel.

In the accompanying drawings the bandage 25 proper is shown in four different constructional forms, while the arrangement for applying these bandages to the skin of the vessel is exemplified in two constructional forms.

80 The bandage itself consists of a layer of asphalt which is either covered with a wire netting or trellis work connected to it by being pressed into it, or in which such a wire netting is embedded. In place of such layer 85 of asphalt also a compound made of tar, rosin, pitch and the like, worked out in form of a layer, may be used.

In the accompanying drawing Figure 1 and 2 represent such a bandage composed of 40 a layer of asphalt or the like *a* with a wire netting *b*, the latter being secured to the asphalt layer by having been pressed into the same. Figs. 3 and 4 show a thicker bandage composed of a thicker layer of asphalt *a'* and a trellis *b'*, such as may be used for closing leaks of larger vessels. Fig. 5 shows a bandage in which a wire-netting or a trellis *b''* is embedded in a layer of asphalt *a''*. Fig. 6 and 7 show a bandage for 45 leaks in large vessels. This bandage consists of a layer of asphalt or the like *a'''* with a wire netting or trellis *b'''* pressed into it. On the side opposite to the trellis *b'''* balls *c'''* are embedded in the asphalt in correspondingly shaped recesses and are held in position by means of a screen *e'''* with corre-

sponding holes, laid over them. This screen *e'''* is again covered with a layer of asphalt *f'''* and secured by means of wire-nails *g'''* to the wire netting or trellis *b'''*. For use this bandage is laid with the side, from which the balls *c'''* project, against the side of the ship, the balls having the object of facilitating the adjustment of the bandage along the skin of the ship. Figs. 8-10 illustrate a constructional form of the arrangement for applying the bandage to the injured part of the skin of the vessel.

This arrangement consists of two or more ropes *h* attached to the bandage *A*, each of 70 these ropes leading to a portable rope winch *i* placed on the deck of the vessel. When the vessel receives a leak *k*, the arrangement described is taken to the bow of the vessel and the bandage with the ropes is dropped over 75 board, so that the ropes with the bandage attached thereto encircle the body of the vessel. Then the winches *i* on deck are moved to a position corresponding to the leak and there fixed. The ropes are now tightened 80 by turning the winches and thereby the bandage is gradually moved over the leak and pressed tightly against it. If the leak is larger than the bandage, first a part of the leak is covered with one bandage and the 85 remaining open part of the leak is covered with further bandages. After the leak has been thus covered and the water, which has entered into the ship has been pumped out, the injured part of the ship's skin can be 90 closed from the inside by means of plates and the like.

According to the constructional form shown in Figs. 11 and 12 rollers *m* are fitted to the body of the vessel, and over these 95 rollers run endless ropes, wire ropes and the like, *n*, encircling the body of the vessel. Between each two of these ropes a bandage *A* is secured. The endless ropes are run on deck over loose pulleys *o*, which are fitted 100 to coupled shafts *p*, which may be engaged by means of a toothed clutch or the like. These shafts are driven by suitable means, preferably an electric motor *r*. When a leak is sprung, that shaft is driven, over 105 which the ropes *n* run carrying the bandage which must be operated for closing the respective leak. If the leak is longer than the length of one bandage, the neighboring bandage is also used, and may also be connected to the preceding bandage by means 110 of an auxiliary bandage. When the leak is

higher than the breadth of one bandage, a second bandage may be secured to the ropes *n* above the first bandage. If in a collision or some other accident two neighboring ropes *n* should be injured bandages A of a suitable length are secured to the next neighboring ropes.

I claim:

1. In a breach mat for vessels, the combination of a sheet of material comprising asphalt; and a wire netting embedded therein.

2. In a breach mat for vessels, the combination of a sheet of asphalt containing material; and a wire netting embedded in one face thereof.

3. A breach mat for vessels comprising a thick layer of flexible material; a plurality of balls embedded in the inner face thereof; and a cover placed on said inner face and having holes through which the balls project, whereby the balls are held in place.

4. A breach mat for vessels, comprising a thick layer of flexible material; a plurality of balls embedded in the inner face thereof; a netting pressed in the outer face thereof; and a cover placed on said inner face and having holes through which the balls project, whereby the balls are held in place.

5. A breach mat for vessels, comprising a thick layer of flexible material; a plurality of balls embedded in the inner face thereof; a netting pressed in the outer face

thereof; a cover placed on said inner face and having holes through which the balls project, whereby the balls are held in place; and another layer of flexible material over said cover.

6. A breach mat for vessels comprising a thick layer of asphalt having recesses in one face thereof; a wire netting pressed into the other face of said layer; balls seated in said recesses respectively and projecting therefrom; a screen having holes registering with the respective balls and laid over the balls and holding them in place; and an additional layer of asphalt covering said screen.

7. In apparatus for placing breach mats on the sides of ships, the combination, with the ship, of a plurality of pairs of pulleys supported on opposite sides of the ship; ropes or the like disposed on corresponding opposite pulleys and passed under the ship; mats carried by each pair of ropes; a source of power; means for at will connecting certain of said pairs of pulleys to said source of power and idler pulleys under said ship and about which the ropes pass.

In testimony whereof, I have signed my name to this specification in the presence of two subscribing witnesses:

DORA LUCKA.
